United States Patent Office.

WILLIAM SWARTS, OF PENT WATER, MICHIGAN.

Letters Patent No. 95,951, dated October 19, 1869.

IMPROVEMENT IN BOOT-PATTERNS.

The Schedule referred to in these Letters Patent and making part of the same.

To whom it may concern:

Be it known that I, WILLIAM SWARTS, of Pent Water, in the county of Oceana, and State of Michigan, have invented a new and useful Improvement in Boot-Packs and Shoe-Packs; and I do declare that the following is a true and accurate description thereof, reference being had to the accompanying drawings, and to the letters of reference marked thereon, and being a part of this specification.

Figure 1 is a view of one side of my invention, as made up in a boot-pack.

Figure 2 is a view of the opposite side of the same.

Figure 3 is a representation of the shape in which the leather for the foot is cut.

The nature of this invention relates to an improvement in the manufacture of boot and shoe-packs; and consists in so cutting the foot that the same is formed from one piece of leather instead of two, as in the pack of ordinary construction, thereby making an article more easy to cut out; that the most leather will be saved; that will be more easy to make; that will be

more durable; and that can be made in better shape, the better to fit the foot.

A, in the drawings, represents the leg of a boot-pack, which is made of one piece, the closing being at the back.

B is the foot, also formed of one piece, formed upon the last, and attached to the leg by the seams C.

By cutting the leather in the shape of fig. 3, to form the foot, both time, labor, and material are largely saved, while a much more serviceable article is obtained.

What I claim as my invention, and desire to secure by Letters Patent, is—

Cutting the foot of a boot or shoe-pack in one piece, of the form specifically shown in fig. 3 of the drawing, and the use of the same for boot-packs, in combination with a leg cut in one piece.

WM. SWARTS.
